UNITED STATES PATENT OFFICE.

OTTO ÖSTER, OF WELLSTON, MISSOURI.

WATER HEATING APPARATUS.

No. 910,016.

Specification of Letters Patent.

Patented Jan. 19, 1909.

Application filed July 31, 1908. Serial No. 446,350.

To all whom it may concern:

Be it known that I, Otto Öster, a citizen of the United States, residing at Wellston, St. Louis county, Missouri, have invented a certain new and useful Improvement in Hot Water Heating Apparatus, of which the following is a full, clear, and exact description, such as will enable others skilled in the art to which it appertains to make and use the same, reference being had to the accompanying drawings, forming part of this specification, in which—

Figure 1 is a diagrammatic view of a hot water heating apparatus constructed in accordance with my invention; Fig. 2 is an enlarged view partly in section of part of said apparatus; and Fig. 3 is a horizontal cross sectional view of the receptacle in which the mercury tube is arranged and also the conduit located adjacent said receptacle.

This invention relates to hot water heating apparatuses, and particularly to the relief valves used in such apparatuses for permitting the water in the system to flow into the expansion tank when a certain pressure is obtained.

The invention relates particularly to that type of valves which have a mercury seal that cuts off the water in the system from the water in the expansion tank, and one object of my invention is to provide a novel valve of the type referred to which is so constructed that the mercury will always follow a certain path and return to its normal position when it is displaced by the pressure of the water in the system.

Another object of my invention is to provide a hot water heating apparatus having a relief valve arranged between the water circulating pipes of the system and the expansion tank, and novel means for cutting said valve out of service and establishing direct communication between the expansion tank and the circulating pipes of the system.

Other objects and desirable features of my invention will be hereinafter pointed out.

Referring to the drawings which illustrate the preferred form of my invention, 1 designates a hot water heater, 2 designates one of the radiators of the system, and 3 and 4, respectively, designate the supply pipe and return pipe that connect the radiator with the boiler of the heater 1. A pipe 5 that communicates with one of the supply pipes of the system establishes communication be-

tween the water circulating pipes of the system and an expansion tank 6 provided with an overflow pipe 7.

A valve is arranged between the pipe 5 and the expansion tank 6 so as to keep the water in the system from entering said tank until a certain pressure is obtained. In the construction herein shown said valve consists of an approximately tubular-shaped receptacle A that communicates with the pipe 5, an open-ended tube B arranged inside of said receptacle and having its lower end terminating a slight distance from the bottom of said receptacle and its upper end projecting through an opening in the top of said receptacle, and a conduit C leading from the lower end of the receptacle A to a water chamber D that communicates with the tube B and the expansion tank. A quantity of mercury E is arranged in the lower end of the receptacle A and in the lower end of the conduit C to form a seal that prevents the water in the system from flowing into the expansion tank until a certain pressure has been obtained.

The lower end of the tube B terminates in a lower horizontal plane than the lower end of the conduit C, and the upper end of said tube also terminates in a lower horizontal plane than the upper end of the conduit C. Consequently, when the water in the receptacle A expands the mercury which lies in the tube B and in the conduit C will be forced upwardly until the mercury in the bottom of the receptacle has been displaced sufficiently to permit the water in said receptacle to rush up the conduit C and thence into the water chamber D from which it passes into the expansion tank. The mercury that has been forced upwardly in the conduit and out of the upper end of said conduit drops downwardly into the upper end of the tube B down which it travels to its normal position in the lower end of the receptacle A. In a valve of this construction the bulk of the mercury always rises in the tube B and the lower end of said tube remains sealed because the pressure in the receptacle A is relieved as soon as the mercury has been displaced from the lower end of the conduit C which is in a higher horizontal plane than the lower end of the tube B. The mercury that is forced upwardly and out of the upper end of the conduit C will never tend to return through said conduit to its normal position for grav-

ity causes said mercury to fall into the upper end of the tube B. Consequently, in an apparatus of this construction the mercury always follows a certain path and never interferes with or impedes the flow of the water that is escaping into the expansion tank.

The receptacle A, tube B and conduit C can be formed in various ways but I prefer to form them in the manner shown in Fig. 2 on account of the low cost of manufacture. The receptacle A consists of a piece of pipe or tubing that has its lower end closed by a hollow cast member 8 provided with a base 9, internal screw-threads that receive screw-threads on the lower end of said pipe, and also a laterally projecting boss 10 into which an elbow 11 is screwed. The upper end of the pipe that forms the body of the receptacle A is screwed into a hollow cast member 12 provided with a transversely extending partition 13 that forms the top of the receptacle A, said partition having a screw-threaded opening that receives the upper end of the tube B. The pipe 5 that leads from one of the supply pipes of the system is provided with an ordinary T 14 and said T is connected to a laterally projecting boss 15 on the member 12 by means of a screw-threaded nipple 16, said boss 15 being located below the transversely extending partition 13. A boss 17 projects laterally from the member 12 above the partition 13, and an elbow 18, which is screwed into said boss, receives the upper end of the conduit C. The conduit C can either consist of a single piece of pipe or be formed in sections that are connected together by a union 19, as shown in Fig. 2. The water chamber D that is located above the partition in the member 12 is formed partly by said member and a piece of pipe 20 that is screwed into the upper end of said member. Instead of having the pipe 20 lead directly to the bottom of the expansion tank 6 I prefer to provide the expansion tank with a downwardly projecting pipe 21 that passes through a cap 22 on the upper end of the pipe 20, the pipe 21 being of less diameter than the pipe 20 and projecting downwardly into same for quite a distance. Another feature of the invention herein described is the novel means whereby I am able to establish direct communication between the pipe 5 that leads from the water circulating pipes of the system and the expansion tank so that the water will not have to pass into the receptacle A and up through the conduit C. One advantage of constructing the apparatus in this manner is that I can convert it into an apparatus in which the water in the system can flow into the expansion tank when only a low pressure has been obtained. Another advantage is that I can establish communication be-

tween the water circulating pipes and the atmosphere when the system is being filled with water or when the water is being drawn off.

The means herein shown for accomplishing the results above referred to consists of a pipe 23 connected to the pipe 5 and tapped into the water chamber D, thus forming a by-pass around the mercury seal valve previously described. The lower end of the pipe 23 is tapped into the T 14 and the upper end of said pipe is tapped into the cap 22, and a valve 24 is arranged in said pipe for cutting off the flow of water therethrough. This valve is normally closed and at such times the water in the system will not flow into the expansion tank until said water has become very hot and thus expanded sufficiently to break the mercury seal that closes the lower end of the conduit C. When it is desired to operate the system at a low pressure the valve 24 is opened so as to cut the mercury valve out of service. When the valve 24 is open the water in the system will flow into the expansion tank as soon as a comparatively low pressure is obtained. I also open the valve 24 whenever I fill the system with fresh water or whenever I run the water out of the system for by opening said valve I establish communication between the circulating pipes of the system and the atmosphere due to the fact that the expansion tank 6 contains air.

Having thus described my invention, what I claim as new and desire to secure by Letters Patent is:

1. A hot water heating apparatus provided with a mercury valve consisting of a closed receptacle that is adapted to be filled with water from the circulating pipes of the system, a water chamber located above said receptacle and having an outlet that is adapted to communicate with an expansion tank or the atmosphere, a conduit located outside of said receptacle and leading from the lower end thereof to said water chamber, a quantity of mercury in said receptacle which normally closes the lower end of said conduit, and a tube in said receptacle having its upper end terminating below the upper end of said conduit and its lower end terminating below the lower end of said conduit, the upper end of said tube communicating with said water chamber; substantially as described.

2. A mercury valve for a hot water heating apparatus comprising a closed receptacle which consists of a piece of pipe or tubing having its ends connected to hollow cast members and adapted to receive water from the circulating pipes of the system, the member at the upper end of said tube having a transversely extending partition which forms the top of said receptacle and also being provided with an outlet that is adapted to com-

- municate with an expansion tank or the atmosphere, a conduit arranged outside of said receptacle and having its lower end connected to said lower cast member and its 5 upper end connected to said upper cast member at a point above said partition, a tube arranged in said receptacle and having its upper end open and passing through said partition with which it coöperates to form 10 a tight joint, the upper end of said tube terminating below the upper end of said conduit, and a quantity of mercury in said receptacle which normally closes the lower end of said conduit; substantially as described.
- 15 3. A mercury valve for a hot water heating apparatus, comprising a closed receptacle which consists of a piece of pipe or tubing having its upper and lower ends connected to approximately tubular-shaped 20 members, the member at the lower end of said pipe being provided with a base and the member at the upper end of the pipe being provided with a transversely extending partition and also being provided with an outlet 25 that is adapted to communicate with an expansion tank or the atmosphere, a supply pipe entering said upper member below said partition, a conduit leading from said lower member and connected to the upper member 30 above said partition, an open-ended tube arranged in said receptacle and having its upper and lower ends terminating in lower horizontal planes than the upper and lower ends of said conduit, the upper end of said 35 tube being open and passing through said partition with which it coöperates to form a tight joint, and a quantity of mercury in said receptacle that normally closes the lower end of said conduit; substantially as 40 described.
4. A hot water heating apparatus provided with a mercury valve consisting of a closed receptacle that is adapted to be filled with water from the circulating pipes of the 45 system, a water chamber located above said receptacle and having an outlet that is adapted to communicate with an expansion tank or the atmosphere, a conduit located outside of said receptacle and leading from 50 the lower end thereof to said water chamber, a quantity of mercury in said receptacle which normally closes the lower end of said conduit, and a tube in said receptacle communicating with said water chamber and having its upper end terminating in a lower horizontal plane than the upper end of said conduit; substantially as described.
5. A hot water heating apparatus provided with a mercury valve consisting of a closed receptacle that is adapted to be filled with water from the circulating pipes of the system, a water chamber located above said receptacle and having an outlet that is adapted to communicate with an expansion tank or the atmosphere, a conduit located outside of said receptacle and leading from the lower end thereof to said water chamber, a quantity of mercury in said receptacle which normally closes the lower end of said conduit, and a tube in said receptacle communicating with said water chamber and having its upper end terminating below the upper end of said conduit; substantially as described.
6. A hot water heating apparatus provided with an expansion tank, a pipe that communicates with the circulating pipes of the system, a tubular-shaped closed receptacle connected to said pipe and adapted to receive water therefrom, a water chamber located above said receptacle and communicating with the expansion tank, a conduit arranged outside of said receptacle and leading from the lower end thereof to said water chamber, a quantity of mercury in said receptacle which normally closes the lower end of said conduit, a tube in said receptacle communicating with said water chamber and having its upper end terminating below the upper end of said conduit, a branch leading from the pipe that communicates with the circulating pipes to said water chamber, and a valve for cutting off the flow of water through said branch; substantially as described.
- In testimony whereof I hereunto affix my signature in the presence of two witnesses, this twenty-seventh day of July, 1908.
